WELT-APPLYING MACHINE

John R. Oliver, Beverly, Mass., assignor to United
Shoe Machinery Corporation, Flemington, N. J.,
a corporation of New Jersey

Application February 13, 1943, Serial No. 475,770

27 Claims. (Cl. 12—51)

This invention relates to machines for operating on shoes and is illustrated herein as embodied in a machine for adhesively attaching strip welting to the bottoms of shoes of the type which have on the bottom margin of the upper an out-turned flange for use in attaching the sole.

In this type of shoe, commonly known as the Ayrlyte shoe, as shown in United States Letters Patent No. 2,301,186, filed November 16, 1939, in the name of F. L. Ayers, the upper and lining are lasted over and secured to a midsole by a line of stitching in such a manner that the marginal edge around the bottom portion of the shoe, which is constituted by the superimposed layers of upper, lining, and midsole, projects outwardly at an angle, thereby forming a bottom flange which runs around the entire shoe. In one method of manufacture, the flange is trimmed and a beveled precoated welting strip is adhesively attached to the abbreviated outturned flange by guiding the beveled edge of the welting strip into the crease between the flange and the upper and simultaneously pounding the beveled edge into engagement with the flange by a reciprocating hammer means, or pressing and squeezing it into engagement with the flange by co-operating pressure rolls. In women's shoes, particularly, this flange is delicate and the treatment received by the beating or rolling action of machines heretofore employed is too harsh and tends to distort the flange, stretching it so that after the welting strip is attached it does not lie close to the upper and, accordingly, does not give a pleasing appearance in the finished shoe. In view of the foregoing, it is an object of the present invention to provide a machine for rapidly and effectively attaching a precoated welting strip to the outturned bottom flange of an Ayrlyte shoe without subjecting it to the harsh treatment referred to above and in such a manner as to insure a permanent bond.

In the attainment of this object, one feature of the machine comprises means for supporting strip welting having a precoated beveled edge in a position to facilitate attaching the welting to the outturned bottom flange of a shoe. As illustrated, the aforesaid supporting means is constructed and arranged to advance successive portions of the welting with its precoated beveled edge exposed for engagement with the flange of the shoe to the position of attachment to enable the operator continuously to attach the welting to the flange of the shoe by turning the shoe and simultaneously pressing its flange in engagement with the beveled edge of the advancing welt-

ing. The supporting means includes spaced members adapted to engage the unattached welting with its beveled edge projecting therefrom and as it is advanced toward the position of attachment, by means provided for this purpose, successive portions of one of the members are caused to move toward the other to squeeze the welting to flatten it and to apply supporting pressure thereto so that when the flange of the shoe it brought into engagement with the beveled edge, the latter will not readily deflect. Cam means is provided for moving the successive portions of the one member toward the other as the welting is presented to the position of attachment, the cam being constructed thereafter to release the portions and thereby to release the welting from supporting pressure so that it may slip from between the members. During the movement of the successive portions of the one member toward the other, they are subjected to repeated blows which tend to still further flatten the welting. This is effected by a reciprocating striker arranged to impart through the cam repeated blows to the successive portions of the one member. The one member comprises a plurality of independently movable sections between which there are slots or spaces, the sections being mounted to move with the opposite member as a unit. The opposite member is also provided with slots corresponding to the slots between the sections, and another feature of the machine resides in a cutting blade mounted for movement through the slots to sever the attached welting laid about the bottom flange of the shoe from the unattached welting adjacent to that section which grips the welting strip at the time it is to be severed. The cutting blade is moved into operation at the will of the operator and, in accordance with still another feature of the machine, means is provided for automatically aligning the slots between one pair of sections of the holding means with the knife. As specifically illustrated, the holding means comprises a disk having a recess in one side near its edge the wall of which has radial slots therein, and a plurality of spaced sectors arranged opposite the wall of the recess, thereby to form spaced surfaces. To align corresponding slots in the walls with the knife, a plunger is provided which is advanced by movement of the knife toward its severing position to enter the spaces between a pair of teeth on a gear fixed to a shaft which rotates the holding means. The gear has teeth in such number that the spaces between the teeth correspond to the slots between the sectors. Rotation of the gear one way or the

other by entrance of the plunger between a pair of teeth produces a corresponding rotation of the holding means, thereby bringing one of the slots into line with the path of movement of the knife.

The invention will now be described with reference to the accompanying drawings, in which

Fig. 1 is a view in side elevation of a machine in which the invention is embodied, a portion of the frame of the machine being broken away to show the construction and arrangement of the operating parts;

Fig. 2 shows the welting strip cutting means advanced to cutting position;

Fig. 3 is a plan view of the machine on an enlarged scale, with parts broken away to show more clearly the driving mechanism;

Fig. 4 is a view in front elevation of the machine, showing the welting strip presenting and supporting means;

Fig. 5 is a section on the line V—V of Fig. 1;

Fig. 6 is a section on the line VI—VI of Fig. 1;

Fig. 7 is an enlarged perspective view of one of the sectors for pressing the welting strip against the face of the disk and the cam for advancing the same; and

Fig. 8 is a section through an Ayrlyte shoe illustrating at the left side the construction of the flange and the disposition of the welting strip in relation to the welt crease and at the right hand side the sole attached to the welting after the flange has been trimmed.

Referring to Fig. 8, it is to be observed that contra to the practice set forth in the above-mentioned Ayers patent the welting strip *w* is adhesively attached to the outturned bottom flange *f* prior to trimming, as shown at the left-hand side of this figure. After the welting strip has been attached to the flange, the flange is trimmed off even with the underside of the welting strip, a filler is pressed in behind the trimmed flange to level the bottom of the shoe, and the outsole is laid over the bottom and stitched to the welting strip, as shown at the right side of Fig. 8.

The apparatus for attaching the welting strip to the untrimmed flange has a hollow frame *10* (Fig. 1) closed at its upper extremity. Near the top of the frame bearings *12* and *14* are formed in the front and back walls and are arranged to receive for free rotation a horizontal drive shaft *16* the ends of which extend beyond the walls of the frame. On the front end of the shaft *16* there is mounted means *18* for holding the welting at a predetermined position to facilitate pressing the flange of the shoe into engagement with the beveled edge of the welting. This means is constructed and arranged frictionally to engage the unattached welting in advance of the predetermined position and to move it to the predetermined position. As illustrated, this means consists, in part, of a disk *20* fastened to the extreme outer end of the shaft. The inner side of the disk *20* is cut away to form a circumferential recess *22* (Fig. 3) and the outer side is beveled at *24* around its outer edge face, for a purpose which will appear hereinafter. Mounted on the shaft *16* behind the disk *20* is a hub *26* having a plurality of openings *28* running parallel to the axis of the shaft which slidably receive stems *30*. Sector-shaped heads *32* are formed at the ends of the stems *30* adjacent to the rear side of the disk *20*, the heads extending radially outward from the shaft toward the circumferential edge of the disk. The faces *34* of the heads *32* are close to the rear side of the disk *20* and beyond the recessed portion *22* form a circumferential wall *36*, which,

with the wall of the recess *22*, provide a circumferential groove *38*. A welting strip *w* is led from a reel *r* into the groove *38* the walls of which frictionally engage the opposite sides of the welting strip, holding it with its beveled edge projecting radially from the disk *20*, as seen in Fig. 1.

By rotation of the disk *20* and hub *26*, which is accomplished by rotation of the shaft *16*, the welting strip is progressively advanced to the position shown in Fig. 1 where the operator may place the shoe in a position to bring that portion of the flange *f* of the shoe *s* adjacent to the welt crease into engagement with the beveled edge of the welting strip. It is to be observed that the beveling *24* at the edge of the disk permits the shoe to be brought close to the projecting welting strip to insure intimate contact without interference from the disk and provides a guide which, by engagement with the welt crease, will hold the shoe from lateral deviation during the attachment of the welting strip. A pulley *40* freely mounted on the outer end of the shaft *16* and connected by belting *42* to a constantly driven pulley *44* journaled on a countershaft *46* at the base of the frame *10* provides means for rotating the shaft *16*. A clutch disk *48* splined on the shaft *16* and slidably into engagement with the side face of the pulley *40* provides means drivably to connect the pulley *49* to the shaft *16*. Movement of the clutch disk *48* is effected by a bell-crank lever *50* one arm *52* of which is forked to engage an annular groove *54* (Fig. 3) formed in the hub *56* of the clutch disk and the other arm *58* of which is connected by a rod *60* to a treadle *62* pivotally mounted near the bottom of the frame *10* at *64*. A spring *66* attached at one end to the treadle *62* and at its opposite end to the frame *10* holds the treadle up so that normally the clutch *48* is out of engagement with the pulley *40*. Rotation of the shaft *16*, and consequently of the welt strip holding means, is produced by holding the treadle *62* down.

The beveled edge of the welting strip and that portion of the flange adjacent to the stitch line with which the beveled edge of the welting strip is to be brought into engagement and adhesively united to form a permanent bond are coated with latex prior to bringing them together. In bringing the precoated surfaces together, the only pressure employed to cause permanent adhesion between the parts is that exerted by the operator in holding the flange of the shoe upwardly against the beveled edge of the welting strip. To make the most of this pressure, the welting strip must be held rigidly at the exact moment and point at which the welting strip and flange are brought into intimate contact and yet prior to this time the welting strip must be free enough to permit relative movement in the groove *38* as the holding means rotates, and immediately following the attachment of the welting strip to the flange it must be entirely free from the groove so that it will remain stuck to the flange and will not be pulled away from it by the advancing movement of the shoe. This is effected herein by an annular cam *68* (Fig. 7) mounted on the frame *10* adjacent to the rear ends of the stems *30*, the outer surface of the cam being of such formation that as the hub *26* rotates the end of each stem *30* successively engages the cam surface and progressively is pushed forwardly. The high point of the cam *68* is opposite the working position so that as each sector-shaped head *32* reaches the working position it will press the welting strip against the inside wall of the recess *22* and rigidly

grip it, as illustrated in Fig. 1. It is to be observed that the pressure brought to bear upon the welt ing by the pressing action of the sectors tends to flatten the welt ing so that it will conform to the shoe. As shown in Fig. 7, the operating portion of the cam 68 extends over an arcuate portion thereof adjacent to its edge, sloping gradually from a low point at 70 to a high point at 72 and then dropping off suddenly at 74. Thus, the grip on the welt ing strip is gradually applied as the welt ing approaches its point of attachment and then is abruptly released so that there is no danger of pulling the welt ing strip away from the flange. As the stems 30 pass beyond the high point of the cam 68 at 72, they are temporarily free to come and go in the hub 26. As they continue their movement and begin again to approach the low point of the cam at 70, they are brought under control so that when the ends of the stems reach the point 70, they will smoothly engage the cam. To this end, notches 76 are provided near the rear ends of the stems 30. The notches are picked up as they approach the top of the cam by an inturned rim 78 of an arc-shaped flange 80 fixed to the edge of the cam 68 and extending from a point near the top of the cam (Fig. 6) around the same to a point adjacent to the low point 70 of the cam. The inturned rim 78 slopes toward the low point 70. As will be seen by reference to Fig. 4, the welt ing strip runs into the groove 38 close to the low point 70 of the cam. The rim 78 holds the heads 32 prior to the engagement of their stems with the low point 70 at a sufficient distance from the wall of the recess 22 to permit ready entrance of the welt ing strip into the groove 38. Frictional engagement of the opposite sides of the welt ing strip is commenced as soon as the ends of the stems engage the low point of the cam.

The welt ing strip usually has some irregularities in thickness. Moreover, as it is led around corners, for example, the tip and heel end of the shoe, it tends to become wavy. The pressure exerted on the welt ing by the heads 32 as they are progressively advanced toward the wall of the recess tends to eliminate any irregularities in its thickness and to flatten it out as it passes around curved portions of the shoe. It is desirable, however, to subject the welt ing strip also to a mild beating action as it is applied to the flange further to flatten the welt ing. This is suitably accomplished by striking the rear ends of the stems 30 of the sector-shaped heads 32 as they advance the welt ing strip and during the attachment of the welt ing strip to the flang. It is to be observed that the blows are imparted to the welt ing strip alone and not to the flange so that there is no danger of damaging the flange. The blows are delivered to the ends of the stems, through the annular cam 68 which is pivoted for this purpose at 82 (Fig. 1) to swing outwardly away from the frame 10, by a striker pin 84 one end of which bears against the rear side of the cam. The striker pin 84 is slidably mounted in a bore 86 formed in the front wall of the frame 10 and may be continuously and rapidly vibrated, except during the cutting-off operation, by a cam-operated driver 88. As illustrated, a head 90 is formed on the rear end of the striker pin 84 which abuts the end of the driver 88. The head 90 is held in contact with a stop pin 94, which limits its outward movement, by a spring 92 disposed between the head and the inside wall of the frame 10. The driver 88 is provided with a

strap 96 which surrounds an eccentric 98 fixed to a shaft 100 journaled in the side walls of the frame. The shaft 100 carries a pulley 102 (Fig. 3) which is connected by a belt 104 to the driven pulley 44' also fastened to the shaft 46 at the base of the frame. Near the middle of the driver 88 a link 106 is connected thereto and to a plunger 108 which passes through an opening 110 in a transverse wall 112 extending across the frame. Below the wall between a flange 114 formed on the lower end of the plunger and the bottom surface of the wall 112 there is placed a spring 116 which pulls the link 106, and consequently the driver 88, downwardly out of contact with the head 90, a stop pin 118 being provided to limit the downward movement of the plunger. A bell crank 120 pivoted at 122 to the frame has one arm 124 connected to the plunger 108. A knee pad 125 is mounted at the end of the other arm 126 of the bell crank whereby when pressure is applied to the knee pad the driver 88 may be raised into contact with the head 90. Thus, the pounding means may be moved into and out of operative position at the will of the operator.

After the welt ing strip has been attached to the entire bottom flange and simultaneously straightened, it is desirable to sever the attached welt ing strip from the succeeding unattached welt ing strip. In order to cut the welt ing strip without pulling it out of the groove 38 and also to cut it at such a point that the cut end will be in readiness for application to the next shoe, that is, so that there will be no forwardly projecting, unsupported end, the welt ing strip is severed by passing a knife through it between the sector-shaped head which grips the welt ing strip at the working point and the preceding head which has just released the welt ing strip. To this end, radial slots 128 (Fig. 4) are formed in the wall of the recess 22, opposite the spaces between successive sector-shaped heads 32, through which the leading end of a knife 130 (Fig. 2) may be passed. As shown, the knife 130 is mounted for sliding movement parallel to the shaft 16 in a guideway 132 formed in the front wall of the frame, an outboard bearing 134 being provided to support and guide the forward end of the knife. The knife is advanced at the will of the operator by downward movement of a cam plate 136 (Fig. 1) having a forwardly sloping cam slot 138 which engages a pin 140 carried by the knife. To pull the cam plate downwardly, a link 142 is fastened thereto and to an arm 144 pivoted at 146 to the frame 10, the forward end of the arm 144 being movable in a clockwise direction about the pivot 146 by a rod 148 connected to a treadle 62 corresponding to the treadle 62' and pivoted to the base of the machine at 64, a spring 66 being provided for holding the treadle in an inoperative position. To make sure that the knife 130 is held in an out-of-the-way position, another spring 150 is provided which is connected to the arm 144 and to the frame 10, the latter spring assisting in holding the arm in a raised position.

In order that one of the openings between the sectors 32 and a corresponding slot 128 in the wall of the recess 22 may be alined with the knife 130 as it is advanced to cut the welt ing strip, means is provided for automatically turning the holding means 18 one way or the other to bring the closest opening and slot in line with the knife. For this purpose a gear 152 is fixed to the shaft 16. The gear has teeth 154 (Fig. 6) thereon which correspond in number and are spaced similarly to the openings between the sectors 32. Be-

low the gear 152 and movable into meshing engagement therewith is a plunger 156. The plunger 156 is slidably mounted in a central bore 158 formed in a rod 160 which passes through the wall 112 and is pivotally connected at its lower end to the rear end of the arm 144 at 162. A spring 164 is disposed behind the plunger 156 at the bottom of the bore 158 and yieldably supports the plunger for sliding movement therein. Since the rod 160 is attached to the arm 144, when the latter is rotated in a clockwise direction to advance the knife the plunger 156 will be moved forwardly to engage a space between one set of teeth 154 and thus operates to turn the shaft 16 and to center one of the openings between the sectors 32 with the advancing knife.

In the operation of the machine, the operator draws the leading end of a welting strip *w* from the reel *r* and pushes it edgewise between the walls of the groove 38 formed by the rear face of the recess 22 in the disk 20 and the front faces 34 of the sector-shaped heads 32 at the point where the welting strip is substantially tangent to the bottom of the groove 38 (Fig. 4). The machine is then started by depressing the treadle 62 so that the holding means 18 rotates, advancing the welting strip to the position shown in Fig. 1. The operator then lifts a shoe to bring that portion of the bottom flange adjacent to the stitch line into engagement with the beveled edge of the welting strip. Pressing the flange firmly against the beveled edge, the operator advances the shoe by rotating it, thus progressively attaching the welting strip to the flange. During this time, by pressing inwardly on the knee pad 125 the welting is flattened by the continuos beating action of the striker pin 84 which, through the cam 68 and stems 39 of the sector-shaped heads 32, impart blows to the rear side of the welting strip. When the welting strip has been led around the entire bottom flange of the shoe, or around such portion of it as is desired, the operator releases the treadle 62, thereby stopping the rotation of the holding means 18, and releases the knee pad 125, thereby withdrawing the striker pin 84 from operation. The knife 130 is then advanced to sever the welting strip by depressing the treadle 62 which simultaneously aligns one of the slots in the holding means 18 with the advancing knife. This completes the operation and upon release of the treadle 62 the machine is ready for the next operation.

Having described my invention, what I claim as new and desire to secure by Letters Patent of the United States is:

1. Means for supporting strip welting having a precoated beveled edge in a position to facilitate attachment of the welting to the flange of a shoe, said means being arranged to present the welting in said position with its precoated beveled edge exposed for engagement with the flange of the shoe and constructed to release the welting from supporting pressure when in said position of attachment to the shoe.

2. Means for supporting strip welting having a precoated beveled edge in a position to facilitate attachment of the welting to the flange of a shoe, said means being arranged to present the welting in said position with its precoated beveled edge exposed for engagement with the flange of the shoe, and said means being constructed to apply pressure to the welting and then to release it from pressure when the welting is in said position of attachment to the shoe.

3. Means for supporting strip welting having a

precoated beveled edge in a position to facilitate attachment of the welting to the flange of a shoe, said means being arranged to present the welting in said position with its precoated beveled edge exposed for engagement with the flange of the shoe and constructed to release the welting from supporting pressure in said position of attachment to the shoe, and means associated with said welt-supporting means arranged to enter the crease between the flange and the shoe upper to position the shoe in proper relation to said welt-supporting means.

4. In a machine for adhesively attaching strip welting to the flange of a shoe, means for engaging a shoe in the angle between the upper and the flange of the shoe to support the shoe, said means being arranged to support strip welting in a position to facilitate attachment of the welting to the flange of the shoe, and means for operating said means while in engagement with a shoe to move successive portions of the welting in position to present its precoated beveled edge for progressive engagement with the flange of the shoe, for applying supporting pressure to said successive portions of the welting as said portions are attached to the flange, and for releasing each portion of the welting from supporting pressure as it is thus attached to the shoe.

5. Means for supporting strip welting having a precoated beveled edge, said means having a portion adapted to engage the shoe in the angle between the upper and the flange of the shoe to support the shoe and having another portion adapted to support strip welting in engagement with said first-named portion in a position to facilitate attachment of the welting to the flange of the shoe, and means for moving said means to present successive portions of the welting strip with its precoated beveled edge exposed for engagement with the flange of a shoe held in engagement with said first-named portion, said second-named portion being adapted to release said welting from said supporting pressure at said position of attachment to the shoe.

6. Means for supporting strip welting having a precoated beveled edge in a position to facilitate attachment of the welting to the flange of a shoe, means for operating said supporting means to present successive portions of the welting in said position, said supporting means being arranged to apply pressure progressively to said successive portions of the welting as they are presented in said position, and means for thus operating said supporting means to apply the pressure and then to release the welting from pressure in said position of attachment to the shoe.

7. Means for supporting strip welting having a precoated beveled edge in a position to facilitate attachment of the welting to the flange of a shoe, said means having spaced parallel members adapted to engage the sides of the welting, means for supporting said means for movement to present the welting in said position with its precoated beveled edge exposed for engagement with the flange of the shoe, and means for effecting such movement, one of said members comprising a plurality of sections individually movable toward the other member, and means for moving successive sections of said one member toward the other to apply progressively increasing pressure to the welting as it is presented in said position and for releasing the welting from supporting pressure when in said position of attachment.

8. Means for supporting strip welting having a precoated beveled edge in a position to facilitate

attachment of the welting to the flange of a shoe, comprising a disk having a surface, a plurality of means associated with the disk having surfaces parallel to the surface of the disk, means supporting said first-named means for movement toward the surface of the disk, the surface of the disk and said first-named means co-operating to engage and support the welting in a position to facilitate attachment of the welting to the flange of the shoe, means for rotating the disk to present successive portions of the welting in said position with its precoated beveled edge exposed for engagement with the flange of the shoe, and means for progressively advancing each of said first-named means in succession toward the surface of the disk as successive portions of the welting are presented in said position to apply supporting pressure to the welting and then to release the welting from supporting pressure.

9. Means for supporting strip welting having a precoated beveled edge in a position to facilitate attachment of the welting to the flange of a shoe comprising a shaft, a disk rotatable therewith, said disk having a surface, means mounted on the shaft having a surface parallel to the surface of the disk and co-operable therewith to support the welting in a position to facilitate attachment of the welting to the flange of the shoe, said means being movable on the shaft to and from the surface of the disk, means for rotating the shaft to present successive portions of the welting in said position with its precoated beveled edge exposed for engagement with the flange of the shoe, and means for progressively moving successive portions of said first-named means toward the surface of the disk to apply supporting pressure to the welting as it is advanced in said position, and being constructed then to release said supporting pressure.

10. In a machine for adhesively attaching strip welting having a precoated beveled edge to the outturned bottom flange of a shoe, a shaft, a disk rotatable therewith, said disk having a surface, a plurality of sections mounted on said shaft for movement to and from the surface of the disk, said sections having surfaces extending radially of the shaft and parallel to the surface of the disk and co-operating therewith to support the welting in a position to facilitate attachment of the welting to the flange of the shoe, means for rotating the shaft to present successive portions of the welting in said position with its beveled edge exposed for engagement with the flange, a projection on each section, and a cam adapted to engage said projections and to cause said sections to move toward the surface of the disk as successive portions of the welting are presented in said position to apply supporting pressure thereto and then to disengage said projections to release said supporting pressure.

11. In a machine for adhesively attaching strip welting having a precoated beveled edge to the outturned bottom flange of a shoe, a shaft, a disk rotatable therewith, said disk having a surface, a hub mounted on said shaft, a plurality of sectors having surfaces extending radially of the hub and parallel to the surface of the disk and co-operating therewith to support the welting in a position to facilitate attachment of the welting to the flange of the shoe, said sectors being slidably mounted on said hub for movement toward the surface of the disk, means for rotating the shaft to present successive portions of the welting in said position with its beveled edge exposed for attachment of the welting to the flange, a

stem fixed to each sector, and a cam adjacent to the free ends of the stems, the contour of said cam being such that the stems are moved to advance each sector in turn toward the surface of the disk to apply progressively increasing pressure to the welting as it is presented in said position.

12. In a machine for adhesively attaching strip welting having a precoated beveled edge to the outturned bottom flange of a shoe, a shaft, a disk rotatable therewith, said disk having a surface, a plurality of sectors adjacent to the surface of the disk having surfaces parallel to the surface of the disk, said surfaces being adapted to support the welting in a position to facilitate attachment of the welting to the flange of a shoe, means for slidably supporting said sectors on said shaft for movement to and from the surface of the disk, means for rotating the shaft to present successive portions of the welting in said position with its beveled edge exposed for attachment of the felting to the flange, a projection fixed to each sector, a cam adjacent to said projections, the contour of the cam being such that it engages the projections as they approach said position and moves the sectors toward the surface of the disk to apply supporting pressure to the welting and then disengages said projections to release said supporting pressure, and means for engaging said projections while they are disengaged by said cam, said means being adapted to move said projections into a position smoothly to be re-engaged by said cam.

13. Means for supporting strip welting having a precoated beveled edge in a position to facilitate attachment of the welting to the flange of a shoe, said means being arranged to present the welting in said position with its precoated beveled edge exposed for engagement with said flange, to apply supporting pressure to the welting, to beat it while subjected to said supporting pressure, and then to release it from the supporting pressure.

14. Means for supporting strip welting having a precoated beveled edge in a position to facilitate attachment of the welting to the flange of a shoe, said means being arranged to present successive portions of the welting in said position with its precoated beveled edge exposed for engagement with said flange, means for applying progressively increasing pressure to said welting as it is presented in said position, and means operable at the will of the operator to impart repeated blows to the welting, said second-named means being constructed to release the welting from the supporting pressure when in said position.

15. Means for supporting strip welting having a precoated beveled edge in a position to facilitate attachment of the welting to the flange of a shoe, said means being arranged to present successive portions of the welting in said position with its precoated beveled edge exposed for engagement with said flange, and means associated with said means to strike the welting a sharp blow in said position of attachment to the shoe thereby to flatten and straighten the welting.

16. Means having relatively movable spaced parallel surfaces for supporting strip welting having a precoated beveled edge in a position to facilitate attachment of the welting to the flange of a shoe, said means being movable to present successive portions of the welting in said position with its precoated beveled edge exposed for engagement with said flange, means for moving one

of said first-named means toward the other to apply supporting pressure to the welting in said position, and means operable at the will of the operator for simultaneously imparting repeated hammer-like blows to said one of said first-named means to cause its surface repeatedly to strike the welting and thereby to flatten and straighten it.

17. In a machine for progressively attaching strip welting having a precoated beveled edge to the outturned bottom flange of a shoe, a disk having a surface, means having a surface parallel to and spaced from the surface of the disk and co-operable therewith to support the welting in a position to facilitate attachment of the welting to said flange, said disk and means being movable as a unit to present the welting in said position with its beveled edge exposed for engagement with said flange, means for effecting such movement, means for moving a portion of said first-named means toward the disk to apply supporting pressure to the welting in said position, and means for simultaneously striking said portion repeated blows.

18. In a machine for progressively attaching strip welting having a precoated beveled edge to the outturned bottom flange of a shoe, a shaft, a disk having a surface, means having a surface parallel to and spaced from the surface of the disk and co-operable therewith to support the welting in a position to facilitate attachment of the welting to said flange, said disk and means being mounted on said shaft and movable as a unit, means for rotating the shaft to present the welting in said position with its beveled edge exposed for engagement with said flange, means for progressively moving successive portions of said first-named means toward the disk to apply supporting pressure to the welting in said position, and a striker operable to impart repeated impacts to said portions when in said position.

19. In a machine for progressively attaching strip welting having a precoated beveled edge to the outturned bottom flange of a shoe, a shaft, a disk mounted on the shaft, said disk having a surface, a plurality of members mounted to turn with said shaft, said members being arranged to provide a substantially continuous surface parallel to and spaced from the surface of the disk and co-operable therewith to support the welting at a position to facilitate attachment of the welting to said flange, each member being movable to and from the disk, means for rotating the shaft to present the welting in said position with its beveled edge exposed for engagement with said flange, a projection on each member, a cam adjacent to said projections, the surface of said cam being formed to engage said projections and to advance each member in succession to within a predetermined distance from the surface of the disk to apply supporting pressure to the welting in said position, and a reciprocable striker pin arranged to bear against said cam and operable to impart through said cam repeated blows to said projections.

20. Means for supporting strip welting having a precoated beveled edge in a position to facilitate attachment of the welting to the flange of a shoe, said means being arranged to present the welting in said position with its precoated beveled edge exposed for engagement with the flange of the shoe to apply supporting pressure and to beat it in said position and then to release the welting from supporting pressure, and means associated with said means to sever the welting adjacent to the position of attachment to the shoe.

21. Means for supporting welting having a precoated beveled edge in a position to facilitate attachment of the welting to the flange of a shoe, said means being adapted to engage the opposite sides of the welting and present the welting in said position with its precoated beveled edge exposed for engagement with the flange of the shoe, slots passing through said means, and a cutting blade mounted to reciprocate in a direction to pass through a given slot to sever the welting adjacent to the position of attachment to the shoe.

5 21. Means for supporting welting having a precoated beveled edge in a position to facilitate attachment of the welting to the flange of a shoe, said means being adapted to engage the opposite sides of the welting and present the welting in said position with its precoated beveled edge exposed for engagement with the flange of the shoe, slots passing through said means, and a cutting blade mounted to reciprocate in a direction to pass through a given slot to sever the welting adjacent to the position of attachment to the shoe.

10 22. In a machine for progressively attaching strip welting having a precoated beveled edge to the outturned flange of a shoe, means having spaced members arranged to engage the opposite sides of the welting and adapted to support the welting in a position to facilitate attachment of the welting to the flange of a shoe, said means being arranged to present the welting in said position with its precoated beveled edge exposed for engagement with the flange of the shoe and constructed then to release the welting from supporting pressure, a plurality of spaced slots passing through said members, a cutter blade mounted for movement in a direction to pass through a slot in the members when in said position, means to effect such movement, and means operable by the initial movement of the cutter blade to align a given slot with the cutter blade.

20 23. In a machine for progressively attaching strip welting having a precoated beveled edge to the outturned flange of a shoe, a shaft, means mounted for rotation therewith, said means comprising spaced members arranged to engage the opposite sides of the welting and adapted to support the welting in a position to facilitate attachment of the welting to the flange of a shoe, means to rotate the shaft to cause said first-named means to present the welting in said position with its precoated beveled edge exposed for engagement with the flange of the shoe and constructed then to release the welting from supporting pressure, slots passing through said spaced members, a cutting blade mounted for movement through said slots, means for advancing said cutting blade, and means operable by said last-named means to align one of said slots with the blade, said means comprising a gear fixed to the shaft, said gear having spaces between teeth thereon corresponding in number to the slots in said spaced members, and a plunger mounted for movement into engagement with the spaces in said gear, said plunger being connected for such movement with said blade-advancing means.

25 24. In a machine for progressively attaching strip welting having a precoated beveled edge to the outturned bottom flange of a shoe, a disk having a surface, means associated with the disk having a surface spaced from and parallel to the surface of the disk and co-operating therewith to support strip welting in a position to facilitate attachment of the welting to the flange of a shoe, a shaft, said disk and means being rotatable therewith to present the welting with its precoated beveled edge exposed for engagement with the flange of the shoe and constructed then to release the welting from the supporting pressure, radial slots passing through said disk and first-named means, and a cutting blade arranged to reciprocate in a direction passing through a

given radial slot to sever the welting adjacent to said position.

25. In a machine for progressively attaching strip welting having a precoated beveled edge to the outturned flange of a shoe, means adapted to support strip welting in a position to facilitate attachment of the welting to said flange, means to move the first-named means to present the welting in said position with its precoated beveled edge exposed for engagement with said flange, slots passing through said first-named means, a cutting blade mounted for movement through said slots, means normally holding said cutting blade in a withdrawin position, means for advancing said cutting blade to a cutting position, and means associated with the cutting-blade-advancing means to aline a slot in said first-named means with the cutting blade.

26. In a machine for progressively attaching strip welting having a precoated beveled edge to the outturned bottom flange of a shoe, means adapted to support strip welting in a position to facilitate attachment of the welting to said flange, means for moving said first-named means to

present successive portions of the welting in said position with its precoated beveled edge exposed for engagement with said flange, means arranged to cause a portion of said first-named means progressively to apply pressure to the welting as it is presented in said position, and means operable to sever the welting in said position.

27. In a machine for progressively attaching strip welting having a precoated beveled edge to the outturned bottom flange of a shoe, means adapted to support strip welting in a position to facilitate attachment of the welting to said flange, means for moving said first-named means to present successive portions of the welting in said position with its precoated beveled edge exposed for engagement with said flange, means arranged to cause a portion of said first-named means to apply pressure to the welting as it is presented in said position, means operable to impart repeated blows to the welting in said position, and means operable thereafter to sever the attached welting from the unattached welting.

JOHN R. OLIVER.
